LEWIS E. MORRISON, OF NEWARK, NEW JERSEY, ASSIGNOR TO HIMSELF AND
MATTHIAS PLUM, BOTH OF NEWARK, NEW JERSEY.

SHEET-REGISTERING MECHANISM.

1,111,968.

Specification of Letters Patent. Patented Sept. 29, 1914.

Application filed December 23, 1910. Serial No. 593,911.

To all whom it may concern:

Be it known that I, Lewis E. Morrison, a citizen of the United States of America, and a resident of Newark, Essex county, New Jersey, have invented certain new and useful Improvements in Sheet-Registering Mechanisms, of which the following is a specification.

This invention relates to sheet registering means and has particular reference to improvements in gages for registering a sheet of paper on the platen of a printing machine.

The objects of the invention are to provide simple, novel and useful register gages adapted to be attached to the platen of a printing machine without in any way disturbing or changing the construction thereof.

To this end the invention comprises gages adapted to be operated to positively register the sheet at both the side and front thereof and of a construction substantially as set forth in the following specification, while reference is had to the accompanying drawings in which—

Figure 1 is a side elevation of a job press, the platen of which is provided with register gages embodying my invention. Fig. 2 is a perspective view of the platen and the gages. Fig. 3 is a detail perspective view of a front gage. Figs. 4 and 5 are detail sectional views of the platen and front gages, and Fig. 6 is a plan view of the side register gages.

In Fig. 1 I have illustrated in outline, a type of job press well known in the art and in which the platen 6 is mounted to oscillate on the pivot 7 in a suitable frame 8. The means for oscillating the platen are well known and not shown. 9 is a feed board from which the paper is fed to the platen. This feed board is illustrative only. 10 represents the usual movable form member operated by a connecting rod 11 from a gear 12, driven in any suitable manner. The above elements are all of well known construction and the operation of this type of press is well understood. The platen is provided with a tympan sheet 13, Fig. 2, held in position by the usual bail 14 pivoted at 15. 16 is the usual gripper bar pivoted at 17 on each side of the platen and to which are attached the usual grippers 18, 18. The gripper bar 16 is mounted on the platen

and operated by the coöperation of the cam 51 carried by the latter and the cam roll 52 carried by the gripper bar so that when the platen moves down into printing position the grippers 18 close down upon the paper to retain it on the platen while the impression is being made and thereafter to strip the paper from the form. The position of the grippers when the platen is up is shown in full lines in Fig. 1 and this operation is well known in the art.

The paper is placed on the platen with its leading or front edge against the front gages 19, 19, and its one side edge against the side gage 20, after which the gages are automatically operated to move the paper into printing position.

Each front gage comprises a pivot block 21 detachably secured to the gripper bar 16 by a thumbscrew 22. The pivot block has further a tongue 23 adapted to enter a groove 24 in the gripper bar to prevent the block from turning on the screw. The pivot block is further provided with hinge lugs 25. In these latter is hinged a short arm 26 by means of a pin 27 the axis of which is parallel to the gripper bar. It should, however, be noted as an essential element of this invention that the axis of the pivot 27 is not coaxial with the axis of the pivots 17 of the gripper bar, the axis of which is in a lower plane. A spring 33 keeps the arm down on the platen. The said arm carries a screw 28 for adjustably securing thereto the gage member 29. This latter has a slot 30 to permit of adjustment as will be understood and is further provided with a stop 31, which rests on the platen. The paper is fed against the stops 31. A guide 32 is frictionally secured to the gage member 29 for the purpose of preventing the sheet from missing the stops 31.

The side register gage 20 comprises a block 35 having a tongue 36 to fit in the aforesaid groove 24 of the gripper bar and is secured to the latter in the same manner as the blocks 21. A gage arm 37 is provided with a hinge lug 38 which is pivoted between the ears 39 and 39' of the block 35 by means of a pin 40. A spring 41 keeps the gage arm against the platen.

It is a feature of this invention that the axis 40 about which the gage turns is inclined to the line through the pivots 17 of the gripper bar as clearly shown in Fig. 6.

and consequently during the operation of the press, the movements of the side gage 20 about this inclined axis and the movement of the platen about the axis 17 causes a relative transverse movement between the gage and the platen. The extent of this movement is indicated by the distance marked 50 in Fig. 6.

The arm 35 carries a stop member 42 having a curved elastic stop 43.

From the foregoing it will be observed that the gages may be adjusted transversely and longitudinally of the platen. The first adjustment is accomplished by loosening the thumbscrews referred to and sliding the blocks 21 along the gripper bar. The second adjustment is accomplished by loosening the screws 28 on the front gage and moving the gage member 29 relatively to the arm 26. 20 The stop member 42 on the side gage may be moved along the arm 35 to adjust the stops 43.

Usually the front gages are positioned between the grippers.

25 The paper 45 is placed on the platen either manually or by an automatic feed with the leading edge against the stops 31 and the one side edge against the stop 43. When the platen moves down into printing position, the gripper bar is brought into alinement with it as shown in Fig. 5 and this movement of the platen causes the stops 31 to move upward on the platen a slight distance thereby pushing the sheet of paper 35 into a predetermined position to receive the impression. The extent of the movement is indicated in Fig. 5 by the distance marked 49. This movement of the gages is due to the fact, above set forth, that the pivot 27 40 is in a higher plane than the pivot 17. Hence the pivot 27 moves in an arc around the pivot 17 toward the platen, and this operation is clearly shown in Figs. 4 and 5.

The downward movement of the platen 45 also causes the lug 38 of the side gage 20 to rotate around the pivot 40, but as this latter is substantially coaxial with the pivot 17 no upward movement of the side gage takes place. Instead the side gage moves 50 sidewise or transversely on the platen because the axis of the pivot 40 is slightly inclined to the axis of the pivot 17, as explained above. The transverse movement of the side gage is illustrated in Fig. 6 as explained and thereby the paper is pushed from the side into printing position. When the form is very large the arm 35 is offset 55 as shown so as to register a large sheet of

paper as will be understood. From this it will be understood that the stops 31 and 43 are adjusted a distance away from the edges of the paper in printing position equal to the extent of the movement of said stops. This insures that the paper is properly registered in the same position for each impression. 65

From the above it will be seen that I have provided very simple and easily attached register gages, and that the same are operated wholly by the movement of the platen relative to the gripper bar. Another 70 advantage of these stops is that they need not be detached when the tympan sheet is to be changed. The gages are simply swung upward in order to raise the bail 14 to free the tympan. After a fresh tympan has been 75 placed upon the platen, the gages are let down and then the register is the same as before.

The invention is susceptible of changes and modification and I claim all such as 80 properly come within the scope of the specification and the claims.

I claim:

1. The combination of a movable platen, a gage support pivoted parallel to the same, 85 a gage pivoted at an angle to the said support pivot and means for oscillating said support to cause the said gage stop to move in an arc in a plane parallel to the surface of the platen. 90

2. The combination of a movable platen, a gripper bar pivoted parallel to the same, a gage block supported on said gripper bar, a gage pivoted on said gage block, the axis of the gage pivot being inclined with respect 95 to the axis of the gripper bar pivot, whereby when said platen is operated the said gage moves transversely of the said platen in a plane parallel to the surface thereof.

3. The combination of a movable platen, 100 a gripper bar pivoted parallel to the same, a gage block adjustably secured to said gripper bar, a gage pivoted on said gage block with the axis of its pivot inclined to the axis of the gripper bar, means for operating 105 said platen to cause the said gage to move transversely of the platen and means for keeping the gage in contact with the surface of the platen.

Signed at Newark, N. J., this 14th day of December, 1910.

LEWIS E. MORRISON.
